(57) **CLAIM**

The ornamental design for a portion of a stand for supporting a speakerphone, as shown and described.

DESCRIPTION

FIG. 1 is a perspective view of a portion of a stand for supporting a speakerphone, showing our new design;

FIG. 2 is a rear elevational view thereof, the portion of a stand not being visible in a front elevational view thereof; FIG. 3 is a right side elevational view thereof, the solid line features of the portion of a stand not being visible in a left side elevational view thereof;

FIG. 4 is a top plan view thereof; and,

FIG. 5 is a bottom plan view thereof.

The broken lines consisting of a long dash and a short dash in FIGS. 2-5 depict a boundary of the claimed design and form no part of the claim.

All other broken lines depict portions of a stand and the speakerphone that form no part of the claimed design.

1 Claim, 5 Drawing Sheets
